UNITED STATES PATENT OFFICE.

JAMES E. BROWN, OF MANSFIELD, OHIO.

DESIGN FOR A CASING FOR STEAM-BOILERS.

SPECIFICATION forming part of Design No. 31,328, dated August 1, 1899.

Application filed December 22, 1898. Serial No. 700,066. Term of patent 14 years.

To all whom it may concern:

Be it known that I, JAMES E. BROWN, of Mansfield, in the county of Richland and State of Ohio, have invented a new and original Design for a Casing for Steam-Boilers, of which the following is a specification, reference being had to the accompanying drawings, forming part of this specification, in which—

My design consists in a steam-boiler casing of the form substantially as shown in the accompanying drawings and as herein described.

The steam-boiler casing, as shown in the drawings, has a chamber 2 at the base, projecting outwardly at the front but not projecting at the rear, the outwardly-projecting portion 5 merging into but being of a less height 20 than the rear portion of the part 2. Above the base portion 2 is the upper portion 3 of the boiler, which upper part is cylindrical in form and is reduced in diameter externally 25 relatively to the lower portion 2, so that there is presented a circular shoulder or ledge 4 of substantial width at the line between said parts.

I claim—

The design for a casing for a steam-boiler 30 as shown and described.

In testimony whereof I have hereunto set my hand.

JAMES E. BROWN.
